UNITED STATES PATENT OFFICE

106,561

DESIGN FOR A PARKING METER

Robert F. Broussard and Charles A. Toce, Houston, Tex., assignors to Parkrite Corporation, Houston, Tex., a corporation

Application August 23, 1937, Serial No. 71,262

Term of patent 14 years

To whom it may concern:

Be it known that we, Robert F. Broussard and Charles A. Toce, citizens of the United States, residing at Houston, in the county of Harris and State of Texas, have invented a new, original, and ornamental Design for a Parking Meter, of which the following is a specification, reference being had to the accompanying drawing, forming part thereof.

Fig. 1 is a front elevation of the parking meter.

Fig. 2 is a fragmentary side elevation of the parking meter.

Fig. 3 is a fragmentary rear elevation of the parking meter.

We claim:

The ornamental design for a parking meter as shown.

ROBERT F. BROUSSARD.
CHARLES A. TOCE.
